UNITED STATES PATENT OFFICE.

FRANK GOFF, OF COLLINGSWOOD, NEW JERSEY.

DRAIN VALVE.

Application filed May 1, 1919. Serial No. 293,952.

The present invention relates to drain or relief valves, such as used for draining or discharging condensation from steam cylinders and the like, and it is the object of 5 the invention to provide a simple and inexpensive valve of that type operable automatically for draining the opposite ends of the steam cylinder of a steam engine in an efficient and practical manner, the construction being such that it is not apt to get out of order.

Another object is the provision of a valve of the nature indicated embodying a pair of balls and seats therefor, with a drain port 15 between said balls, and the arrangement being such that either ball is seatable when necessary to prevent the escape of steam; that ball which is seated unseating the other one automatically, to provide for alternate 20 seating of the balls as the piston is moved back and forth, said balls also serving as check valves for preventing air being drawn into the cylinder, and in the absence of pressure permitting the water of condensation 25 to drain from both ends of the cylinders, as well as preventing back pressure from passing the valve and reaching the cylinder.

A further object is the provision of such 30 a valve comprising but few parts, and having means whereby wear can be taken up.

A still further object is the provision in 35 a valve as above set forth of means in addition to the fluid escape port, from which a pipe may lead upwardly, means whereby 40 accumulated water of condensation can drain out, when pressure is relieved, as when the engine is idle.

With the foregoing and other objects in 45 view, which will be apparent as the description proceeds, the invention resides in the construction and arrangement of parts hereinafter described and claimed; it being understood that changes can be made within the scope of what is claimed without departing from the spirit of the invention.

The invention is illustrated in the accompanying drawings, wherein—

Figure 1 is a side elevation of the valve 50 as applied to the cylinder of a steam engine.

Figure 2 is a vertical section of the valve showing the balls in elevation.

Figure 3 is a plan view of the valve showing the secondary drainage means, portions being broken away and shown in section.

Figure 4 is a median section of the secondary drainage valve, portions being shown in elevation.

Figure 5 is a sectional detail of a modified form of secondary drainage valve.

The main valve embodies a casing 1 having formed therein between its ends the opposite conical valve seats 2 and 3 facing the opposite ends of the casing away from one another, and the casing has the reduced bore or portion 4 between said seats, and the bores 5 of larger diameter extending from the seats 2 and 3 toward the opposite ends of the casing and terminating in counter bores 6 in the end portions of the casing which are internally threaded; there being shoulders 7 between the bores 5 and counter bores 6. The casing is provided at one side between its ends with a lateral nipple 8, and an escape or fluid outlet port 9 leading from the portion 4 between the valve seats to the passage of the nipple. This nipple is threaded for the attachment of a drain pipe which can be led to any suitable point of discharge for the water and vapor.

Nipples 10 are provided at the opposite 80 ends of the casing 1 and constitute removable ends for the casing, said nipples being provided with enlarged end portions 11 which are screw threaded into the bores 6, and which are also provided therein with the conical valve seats 12 confronting the respective seats 2 and 3, and the passages of the nipples 10 taper from 85 said seats 12 to the outer end portions of the nipples which are screw threaded for the 90 connection of piping or fittings. Several superposed washers 13, which are of suitable thin material, are disposed between each shoulder 7 and the portion 11 of the corresponding nipple 10, and provide means 95 whereby wear can be taken up as the seats wear under the constant action of the valve members. Thus, by removing the nipples 10 from time to time, one or more of the washers 13 can be removed, and when the 100 nipples are then again screwed tight, this will bring the valve seats closer together to compensate for the wear, and thus avoid the excessive movement of the valve members in seating.

The valve members comprise two balls 14 and 15, one disposed loosely between the valve seat 2 and corresponding seat 12, and

the other disposed between the seat 3 and corresponding seat 12, and said balls will ordinarily rest in the valleys or grooves between the seats, the casing 1 being arranged 5 with its axis horizontal. Each ball normally rests against both seats between which it is disposed, so as to roll up the lower inclined portion of either seat to seat itself within and against the corresponding seat, and the 10 portion 4 is of short length, the two seats 2 and 3 being sufficiently close together, that both balls 14 and 15 cannot seat against the seats 2 and 3 simultaneously. It will be noted that when one of the balls seats it 15 will project into the portion 4 beyond the center thereof, so that when the other ball is seated it will unseat the first named ball.

The nipples 10 afford means for connecting the ends of the casing with the ends of 20 a steam cylinder. Thus, piping and fittings 16 and 17 connect the nipples 10 with the opposite ends of the cylinder 18, said connections being made at the bottom of the cylinder so that condensation will drain 25 downwardly into the valve.

In operation, when the engine is idle, the balls 14 and 15 will roll into the grooves between the valve seats, as seen in Figure 2, thereby permitting any water to drain from 30 either end of the cylinder past the balls 14 and 15 to the portion 4 of the casing and out through the port 9. When the engine is in operation, the valve provides for the alternate discharge of water of condensation 35 from the opposite ends of the cylinder. Thus, referring to Figure 1, supposing that steam is admitted into the left hand end of the cylinder 18, the steam pressure in passing through the piping 16 will be brought to 40 bear against the wall 14, thereby rolling it against the seat 2, and preventing the escape of steam through the port 9. Then, when the piston is reversed, and steam admitted into the right hand end of the cylinder 45 18, the steam in passing down through the piping 17 will seat the ball 15 against the seat 3, and this ball 15 in being seated under pressure will unseat the ball 14 against the lower pressure in the left hand end of the cylinder. Consequently, any water or vapor 50 in the left hand end of the cylinder can now drain out through the port 9 past the ball 14, and then when the ball 14 is again seated by the flow of steam into the left 55 hand end of the cylinder, the ball 15 is unseated and drainage from the right hand end of the cylinder permitted. The balls 14 and 15 are thus alternately seated, one unseating the other, and this movement of the 60 balls correspond in movement to the back and forth motion of the piston, and provides for alternate drainage from the opposite ends of the steam cylinder as the engine is in operation. As soon as the engine comes 65 to rest, the balls 14 and 15 will both unseat,

permitting drainage from both ends of the cylinders. The operation is entirely automatic, and the construction and operation is extremely simple, with a minimum number of parts. The seats 12 are provided, in order 70 that the balls 14 and 15 will serve as check valves for preventing cold air or water of condensation being drawn into the cylinder, such as when the engine is idling with sub-atmospheric pressure in the cylinder. The balls 14 and 15 in bearing against the seats 12 will prevent cold air being drawn into the cylinder, and, should any water of condensation collect in the casing 1 and pipes 16 and 17, after the engine has 75 been stopped, such water is prevented from being drawn back into the cylinder because the balls 14 and 15 in seating against the seats 12 will prevent such reverse flow when the pressure within the cylinder is below atmospheric pressure. The balls 14 and 15, in the absence of pressure in either direction, will normally assume intermediate positions, as seen in Fig. 2, with said balls contacting with both seats 12 and the seats 2 and 3. 80 Said balls are arranged to roll upwardly and downwardly on the bottom portions of the valve seats to closed and open positions, so that when there is no pressure against the balls in either direction, the balls will 85 roll by gravity away from the seats against which they bear to neutral or intermediate positions between and in contact with the corresponding valve seats. The casing is therefore arranged with its axis horizontal, 90 the axis of the valve seats coinciding with the axis of the casing.

A secondary drainage valve is used in addition to the main valve as an auxiliary means of drainage, especially when a pipe 105 leads upwardly from the nipple 8 as seen in dotted lines in Fig. 1, which would ordinarily prevent the drainage of water from the cylinder when the engine is at rest. The casing 1 is provided opposite to the nipple 8 with an outstanding boss 19 and a drain or escape port 20 opposite to the port 9 extending from the portion 4 into the boss, and the secondary or auxiliary drain valve 21 is attached to the boss 19. The main valve 110 is preferably disposed with the nipple 8 and boss 19 in a horizontal plane, with the nipple at one side and the boss at the opposite side. The secondary drain valve 21 as shown is of the same general construction of the relief 115 valve disclosed in my Patent No. 1,305,598, granted June 3, 1919, with slight variations, although other forms of valves can be used for this purpose, which will permit of the drainage or discharge of fluid under atmospheric low pressure, but which will prevent such flow when the velocity of the fluid through the valve increases above a predetermined amount. Briefly described, the valve 21 embodies a casing 22 having a bore 120

23 and chamber 24, with a reduced portion 25 between them, and an escape port 26 extending from the chamber 24 in alignment with the bore 23. There is a valve seat 27 at the inner end of the port 26 adjacent to the chamber 24, and the casing has a lateral nipple 28 at one side, the passage 29 of which extends to the chamber 24 adjacent to the valve seat 27. This nipple 28 is screwed into the boss 19 to bring the passage 29 into communication with the port 26, and the casing 22 can be disposed in any desired angular position. A valve plunger 30 is slideable in the portion 25 and has the valve 31 at one end to seat in the conical seat 27, for closing the outlet, and the opposite end of the plunger 30 has a head or flange 32 slideable in the bore 23 to assist in guiding the plunger. A cap 33 is screwed removably over the end of the casing 22 opposite the port 26 to close the bore 23 and limit the unseating movement of the valve member or plunger, and a coiled wire expansion spring of suitable tension surrounds the plunger 30 within the bore 23 and is confined between the head 32 and the shoulder at the inner end of the bore 23. This spring 34 is of desired tension so as to hold the valve member 30 open until the velocity of the fluid flowing from the passage 29 through the chamber 24 and port 26 increases to a predetermined amount, in which event the suction action of the fluid discharging through the port 26 will draw the valve member 30 to the seat 27. The pressure will then build up slightly to hold the valve member against said seat 27, to prevent further escape of fluid. The valve member 30 will open automatically as soon as the pressure is reduced to a point to enable the spring 34 to assert itself, thereby letting the water and moisture drain out. The head 32 being slideable in the bore 23 and the plunger 30 being slideable in the portion 25 will of course permit of leakage of fluid past the portion 25 and head 32 so that the plunger 30 is free to slide longitudinally.

By using this secondary drain valve with the main drain valve, even though the water cannot discharge through the port 9, because of a pipe leading upwardly therefrom, such water can drain through the valve 21, when the valve member or plunger 30 is raised by the spring 34, such as when the engine is idle. When the engine is in operation, the valve member or plunger 30 is seated immediately when there is an effort for the steam to discharge through the passage 29 and port 26. Thus, each puff of steam will seat the valve member or plunger 30, the sudden flow of steam through the passage 29 and port 26 immediately creating a suction effect that seats the valve member 30, and as soon as the pressure is relieved, the spring 34 opens the valve mem-

ber 30. The force of the spring 34 is such that when the valve member 30 is seated against the seat 27 the pressure of the steam in discharging will be sufficient to hold the valve member seated, but the spring will 70 unseat the valve member as soon as the pressure of the steam against the valve member is relieved. If the steam is discharged in rapid succession from the opposite ends of the cylinder, the impulses may be sufficiently 75 rapid to practically hold the valve member seated, whereas if the engine is running slow, the valve member 30 may be alternately seated and opened.

Figure 5 illustrates a modification, in 80 which a more simple secondary drain valve is used. Thus, a cap 22' is screwed over the boss 19 of the casing 1, and has a bore or chamber 24' in which a valve member 30' in the form of a ball is free to move, said cap 85 having an escape port 26' leading from the bore 24', with a valve seat 27' between said port and chamber and against which the ball 30' is seatable by a puff of steam from within the casing 1, to ordinarily prevent the escape 90 of fluid. Said ball will roll away from the seat 27' in the absence of sufficient pressure to hold it against the seat 27', thereby opening the port 26', and permitting water to 95 drain out. The boss 19 can be provided with a conical valve seat 20' at the outer end of the port 20 against which the ball 30' is seatable to prevent the inflow of air.

When the discharge passage from the port 9 does not lead upwardly, so that water of 100 condensation will not collect therein, the secondary valve 21 may be omitted.

Having thus described the invention, what is claimed as new is:

1. A drain valve for a steam engine cylinder comprising a casing having end portions provided with passages to communicate with the opposite ends of an engine cylinder and having an escape port between said passages, valve balls within the casing 105 between said port and passages, said end portions having conical valve seats between the balls and passages against which the balls are seatable toward said passages to prevent back flow into the cylinder, the casing having conical valve seats between said 110 port and balls against which the balls are seatable toward said port, the last named valve seats being so close together as to permit the balls to contact directly with one another between said last named valve seats 115 so that one ball when seating against the corresponding last named valve seat will unseat the other ball from the other last named valve seat.

2. A drain valve for a steam engine cylinder comprising a casing having end portions provided with passages to communicate with the opposite ends of an engine cylinder and having an escape port between 120

said passages, valve balls within the casing between said port and passages, said end portions having conical valve seats between the balls and passages against which the balls are seatable toward said passages to prevent back flow into the cylinder, the casing having conical valve seats between said port and balls against which the balls are seatable toward said port, the last named valve seats being so close together as to permit the balls to contact directly with one another between said last named valve seats so that one ball when seating against the corresponding last named valve seat will unseat the other ball from the other last named valve seat, the interior of the casing between the first named and last named valve seats being of larger diameter than the balls to permit free lateral movement of the balls when they are located intermediate the first named and last named valve seats and to provide for the upward and downward rolling movement of the balls on the lower portion of the valve seats when seating and unseating.

3. A drain valve for a steam engine cylinder comprising a casing having end portions provided with passages to communicate with the opposite ends of an engine cylinder and having an escape port between said passages, valve balls within the casing between said port and passages, the casing having conical valve seats between said port and balls against which the balls are seatable toward said port, said valve seats being so close together as to permit the balls to contact directly with one another between said valve seats so that one ball when seating against the corresponding valve seat will unseat the other ball from the other valve seat, the interior of the casing between said passages and valve seats being of larger diameter than the balls to permit free lateral movement of the balls when they are removed from said seats and to provide for the upward and downward rolling movement of the balls on the lower portions of the valve seats when seating and unseating.

4. A drain valve embodying a casing having oppositely facing valve seats and two escape ports extending from between said valve seats, valve members seatable against

said seats at the opposite sides thereof and arranged for alternate seating thereof, the seating of one valve member unseating the other, one of said ports being for the normal discharge of water and steam during working conditions, and means permitting water to drain through the other port in the absence of steam pressure from within said casing and operable to stop the flow of water and steam therethrough when subjected to steam pressure from within the casing.

5. A drain valve embodying a casing having oppositely facing valve seats and two escape ports extending from between said seats, one of said ports being the normal outlet for water and steam from within said casing, valve members within the casing at the opposite sides of said seats arranged to seat alternately, one valve member in seating unseating the other, and a secondary valve for the other port arranged to open in the absence of steam pressure for the drainage of water through the last named port and arranged to close under steam pressure from within the casing to prevent the escape of steam so that it will pass through the first named port.

6. A drain valve embodying a casing having oppositely facing valve seats, and escape ports leading from between said seats, one port being for the normal discharge of water and steam from the casing, valve members within the casing at the opposite sides of said seats and seatable alternately, one valve member in seating unseating the other, a member attached to the casing in communication with the other port for the drainage of water from the casing and having an escape port and valve seat, and a valve member movable in the last named member and movable away from said seat in the absence of steam pressure from within the casing to permit water to drain out through said escape port, and arranged to seat under steam pressure from within the casing to prevent the escape of steam through escape port and direct the steam and water through the first named port.

In testimony whereof I hereunto set my hand.

FRANK GOFF.
